MEANS FOR AND METHOD OF SEPARATING
SHEET MATERIAL

Robert Reinartz, Offenbach-on-the-Main, Germany, assignor, by mesne assignments, to Arthur Wormser, Offenbach-on-the-Main, Germany

Application November 15, 1934, Serial No. 753,212
In Germany December 6, 1933

23 Claims. (Cl. 271—28)

This invention relates to sheet separating devices for sheet feeding machines and has for its object to provide a device by which the sheet separating effect of suction nozzles is improved.

5 In the accompanying drawing:

Figure 1 is an elevation partly in section of a suction device embodying my invention;

10 Figs. 2 to 6 are diagrammatic sections of the device shown in Fig. 1 with certain parts omitted for the sake of clarity, indicating successive positions of the device during its operation;

15 Figs. 7 to 10 are similar sections of different modifications of my invention.

In the bearings 1, 2 of a fork 3 a cylindrical suction nozzle 4 is supported to the interior 5 of which a suction effect is applied by a flexible tube 6. The vertical and horizontal motions of the fork 3 and the rocking of the suction nozzle 4 around its axle 7 are dependent on the manner of application of the suction device in the feeding machine, and need not be described in detail herein.

20 On the axle 7 of the suction nozzle 4 is loosely mounted a specially shaped arm 8 which by means of a connecting rod 9 is given a rocking motion around the axis of the suction nozzle. A small rod 10 is fixed to the arm 8 so that said rod continuously moves concentrically to the axis of the suction nozzle 4 close to its cylindrical surface.

25 The operation of this simple device is as follows:

30 In Fig. 2 the suction nozzle is near the stack 11 of sheets 13 so that the opening 12 or a series of openings disposed on the surface of the suction nozzle 4 parallel to its axis touches the stack or is near the point of contact. The connecting rod 9 has brought the arm 8 in such a position that the separating rod 10 is on the right of the openings 12 and does not touch the surface of the stack or touches it only slightly.

35 Now suction is applied and the nozzle 4 is slightly raised as shown in Fig. 3, so that the separating rod 10 which now begins moving to the left from the position shown may enter between the suction nozzle 4 and the top sheet 13. The nearer the separating rod 10 comes to the openings 12 the more the sheets 13, sucked on by the nozzle, are deflected. The effect of this deflection is that one or more excess sheets sucked on fall down. Generally the motion of the separating rod 10 may end in the position shown in Fig. 3.

40 But the separating effect is even more reliable if the separating rod 10 is caused to pass by the 45 openings 12 until it reaches the lefthand side of

the suction nozzle 4. This motion is shown in Figs. 4 to 6 which are self-explanatory. The reason for the improved separating effect of this motion of the separating rod may be explained by the fact that the deflection of the sheet runs 5 over its surface like a wave and by the fact that temporarily the sheet is slightly lifted from the suction opening and the suction effect is much diminished (Fig. 4.)

10 While the rod 10 is passing between the suction nozzle and the pile, the vertical motion of the suction nozzle may be interrupted as shown in Figure 4. The nozzle 4 is suitably supported by a pair of levers 15 fulcrumed at 16 and engaging the axle 7. The other end of the levers is 15 provided with a roller 17 held in contact with the cam 18 by the resilient means 20. The cam is rotated to cause vertical movement of the nozzle but the contour of the cam is such as to provide for an interruption in the vertical movement at 20 a predetermined point in the movement of the separating rod 10. The effect of this interruption is that excess sheets gripped by the suction nozzle, must fall back a small distance only; but if time enough is available the suction nozzle may 25 raise without any interruption.

15 In the modifications shown in Figs. 7 and 8 the separating rod 10 has not a circular section, but a section similar to a mushroom or to a crescent. Experience has shown that very thin 30 papers are sucked into the sharp angle between the suction nozzle and the separating rod and may be mutilated. This is prevented if the knife-like part of the profile of Figs. 7 and 8 fits closely to the surface of the nozzle. But as in this case 35 the large surface of contact between the separating rod and the suction nozzle would completely close a single series of openings 12 and therefore as it is to be feared that the correctly sucked on sheet would fall down when the machine moves 40 slowly, a second series of openings 14 is provided at such a distance from the principal series of openings 12 that at least one series of openings is always open. The second series of openings may consist of smaller holes than the principal 45 openings such as is shown in Figs. 7 and 8.

20 In Fig. 7, 15 designates a finger which presses down the surface of sheet 13 while the rod 10 passes between the suction nozzle and the sheet. In spite of the fact that the separating rod 10 50 causes the sheet 13 to participate in its motion far less than might be anticipated so that in general it is unnecessary to hold the sheet 13, in some cases it is desirable to prevent any shifting of the sheet 13 relatively to the nozzles 12. 55

The separating effect may be further assisted by a rocking of the suction nozzle 4 around the axle 7. In this case the total stroke of the separating rod 10 may be so long that it has completely passed by the openings after the suction nozzle has been rocked as shown in Fig. 9.

Instead of being cylindrical, the suction nozzle may be provided with a flat suction plane as shown in Fig. 10. In this case the separating rod 10 moves to and fro in a horizontal path.

The suction nozzle 4 provided with a separating rod 10 like any other one may be disposed in the middle of a sheet edge or near the corner. In the first case it is desirable to move the separating rod from inside against the edge and in the second case against the corner.

I claim—

1. A separating device for sheet feeding machines comprising a suction nozzle mounted adjacent a stack of sheets for sucking the sheets from the stack, and a member movable parallel to the face of said nozzle and between the nozzle and the top sheet of the stack to deflect the sheets from the nozzle to release the excess sheets from the nozzle.

2. A separating device for sheet feeding machines comprising a suction nozzle mounted adjacent a stack of sheets for sucking the sheets from a stack, and a member movable parallel to the face of said nozzle and between the suction nozzle and the suction engaged top sheet of the stack to deflect the sheets from the nozzle whereby excess sheets sucked from the stack are released by the nozzle.

3. A separating device for sheet feeding machines comprising a suction device having a suction aperture therein and movable in close proximity to a stack of sheets to be separated, and a rod movable above said stack parallel to the face of said suction device, between the suction engaged sheet and said aperture for deflecting sheets from the suction device.

4. A separating device for sheet feeding machines comprising a nozzle member having a series of apertures therein for sucking sheets from a stack arranged beneath the apertures, and a deflecting rod movable between the suction engaged sheet and said apertures parallel to the face of said nozzle member for deflecting the sheets from the nozzle.

5. A separating device for sheet feeding machines comprising a nozzle member having a series of apertures therein for sucking sheets from a stack arranged beneath the apertures, and a deflecting rod movable above the stack parallel to the face of said member and between the suction engaged sheet and said member and having a profile section which clings knife-like to the nozzle member.

6. A separating device for sheet feeding machines comprising a nozzle member having a plurality of series of suction apertures suitably spaced apart, and a deflecting member movable between the suction engaged sheet and said member and parallel to the face thereof for successively cooperating with different series of apertures.

7. A separating device for sheet feeding machines comprising a vertically movable nozzle member having a series of apertures therein for sucking sheets from a stack arranged beneath the apertures, a deflecting rod movable beneath said apertures for deflecting the sheets from the nozzle, the movement of said nozzle being in-

terrupted during the passage of the deflecting rod beneath the apertures.

8. In separating mechanism for sheet material, the combination of means for causing sheet material to be withdrawn from a pile, and means located exteriorly of said aforesaid means and movable between the latter and a sheet being in contact therewith for separating the second sheet from the first sheet if a second sheet adheres to the first sheet.

9. A separating device for sheet feeding machines comprising a suction nozzle mounted adjacent a stack of sheets for sucking the sheets from the stack, and a member located exteriorly of said nozzle and movable between said nozzle and a sheet directly engaged thereby to deflect the sheet from the nozzle to release excess sheets thereunder.

10. The method of separating the top sheet from a stack of sheets consisting in withdrawing the top sheet from the stack, then partially stripping the withdrawn sheet from the separating means by buckling it for separating a second sheet from said withdrawn sheet if the second sheet adheres to the latter sheet.

11. The method of separating the top sheet from a stack of sheets consisting in withdrawing the top sheet from the stack, then deflecting the withdrawn sheet from the separating means by buckling it for separating a second sheet from said withdrawn sheet if the second sheet adheres to the latter sheet.

12. The method of separating the top sheet from a stack of sheets for the purpose of advancing sheets to a sheet handling machine, consisting in engaging the top sheet of a stack by a pneumatic member, raising said pneumatic member together with a sheet above the level of said stack, moving a member parallel to the face of said pneumatic member and between the latter and the sheet engaged thereby, to thereby deflect said sheet from said pneumatic member for the purpose of releasing any excess sheets adhering to said top sheet.

13. The method of separating the top sheet from a stack of sheets for the purpose of advancing sheets to a sheet handling machine, consisting in engaging the top sheet of a stack by a suction member, raising said suction member together with a sheet above the level of said stack, moving a member parallel to the face of said suction member between the latter and the sheet engaged thereby and across the suction aperture or apertures thereof, to thereby deflect said sheet from said suction member for the purpose of releasing any excess sheets adhering to said top sheet.

14. The method of separating by suction the top sheet from a stack of sheets consisting in withdrawing the top sheet from a stack by suction, temporarily slightly lifting said sheet from suction influence, and deflecting said sheet from the exterior of the suction medium for the purpose of releasing any excess sheets adhering to said top sheet.

15. In a separating mechanism for sheet material, the combination of relatively movable means comprising, a suction member having an air opening for withdrawing sheet material from a pile, a sheet deflecting member located exteriorly of said suction member and adapted to partially seal said opening in said suction member and deflect a sheet engaged directly and held by said suction member until the end of the relative movement of said means from the latter for the purpose of re-

leasing any excess sheets adhering to said sheet.

16. In a separating mechanism for sheet material, the combination of relatively movable means comprising, a suction member having an air opening for withdrawing sheet material from a pile, a sheet deflecting rod located exteriorly of said suction member and having a diameter less than the dimension of the air opening in said suction member to partially seal said air opening and deflect a sheet engaged directly and held by said suction member until the end of the relative movement of said means from said suction member for the purpose of releasing any excess sheets adhering to said sheet.

17. In separating mechanism for sheet material, the combination of means withdrawing sheet material from the pile, and means located exteriorly of said aforesaid means and arranged to move between the latter and a sheet being in contact therewith up to a point adjacent to the sheet engaging part of said withdrawing means for the purpose of deflecting such sheet from said withdrawing member and releasing thereby any excess sheets adhering to said sheet.

18. In separating mechanism for sheet material, the combination of means withdrawing sheet material from the pile, and means located exteriorly of said aforesaid means and arranged to move between the latter and a sheet being in contact therewith up to a point opposite the sheet engaging part of said withdrawing means for the purpose of deflecting such sheet from said withdrawing member and releasing thereby any excess sheets adhering to said sheet.

19. In separating mechanism for sheet material, the combination of means withdrawing sheet material from the pile, and means located exteriorly of said aforesaid means and arranged to move between the latter and a sheet being in contact therewith up to a point beyond the sheet engaging part of said withdrawing means for the purpose of deflecting such sheet from said withdrawing member and releasing thereby any excess sheets adhering to said sheet.

20. In a separating mechanism for sheet material, the combination of relatively movable means comprising, a sheet separating member arranged to engage and withdraw sheet material from a pile of sheets, and a deflecting member located exteriorly of said separating member and adapted to deflect the sheet, the relative movement of said members being terminated when said deflecting member and the sheet engaging part of said separating member are adjacent each other.

21. In a separating mechanism for sheet material, the combination of relatively movable means comprising, a sheet separating member arranged to engage and withdraw sheet material from a pile of sheets, and a deflecting member located exteriorly of said separating member and adapted to deflect the sheet, the relative movement of said members being terminated when said deflecting member and the sheet engaging part of said separating member have reached a position opposite each other.

22. In a separating mechanism for sheet material, the combination of relatively movable means comprising, a sheet separating member arranged to engage and withdraw sheet material from a pile of sheets, and a deflecting member located exteriorly of said separating member and adapted to deflect the sheet held by said separating member until after said deflecting member and the sheet engaging part of said separating member have passed each other.

23. In separating mechanism for sheet material, the combination of a member for withdrawing sheet material from a pile of sheets and means located exteriorly of said aforesaid member and movable between the latter and a sheet being in contact therewith for deflecting said sheet from said withdrawing member, and means for interrupting the movement of said withdrawing member during movement of said exteriorly located means.

ROBERT REINARTZ.
